UNITED STATES PATENT OFFICE.

FREDERICK G. FOLBERTH AND WILLIAM M. FOLBERTH, OF CLEVELAND, OHIO, ASSIGNEES TO TRICO PRODUCTS CORPORATION, OF BUFFALO, NEW YORK, A CORPORATION OF NEW YORK.

WINDSHIELD CLEANER.

Application filed March 20, 1924. Serial No. 700,659.

This invention relates to windshield cleaners, and more particularly to suction operated cleaners adapted to be operated by the suction of the intake manifold of an internal combustion engine.

An object of the invention is to provide a cylinder construction comprising two halves or sections of a cylinder and clamping means for securing the two sections to each other. More specifically, we provide a cylinder formed in two sections, each section of which is provided with a cylinder head at its outer end and is provided with a flared edge at its inner end and a grooved clamping member adapted to surround the contacting flared inner ends of the cylinder sections to secure them to each other.

A further object of the invention is to provide improved valve shifting mechanism for a motor of this character.

A still further object is the provision of valve shifting mechanism consisting of a pivoted member adapted to be swung on its pivot by a moving part of a motor, a spring connected to said pivoted member and adapted to be maintained under tension, and a valve supporting member adapted to be engaged by said pivoted member to automatically shift the valves of the cleaner motor.

In the accompanying drawings, we have shown one embodiment of this invention. In this showing:

Figure 1 is a perspective view of a windshield cleaner constructed according to the present invention.

Figure 2 is a vertical transverse sectional view through the cleaner when in position on a windshield.

Figure 3 is a perspective view of one of the sections of the cylinder.

Figure 4 is a vertical sectional view substantially on line 4-4 of Figure 2 showing the valve shifting member.

Figure 5 is a similar view substantially on line 5-5 of Figure 2, showing the manner in which the valve shifting member is engaged by a movable part of a motor.

Figure 6 is a horizontal sectional view through a portion of the cylinder and closure member showing the passages in the closure member,

Figure 7 is an exterior elevation of the closure plate, parts being shown in section,

Figure 8 is a detail view of the valve shifting mechanism, and,

Figure 9 is a similar view of the clamp.

Referring to the drawings, the reference numeral 1 designates a windshield frame of the usual construction having a pane of glass 2 or other transparent material arranged therein. The cleaner motor, shown as a cylindrical casing, is designated generally by the reference numeral 3, and is adapted to be arranged on the interior of the windshield frame, as shown. The motor is provided with a transverse power shaft 4 adapted to be oscillated and the outer end of this shaft is adapted to receive a cleaner arm 5. The shaft is provided with a transverse passage for the reception of the end of the cleaner arm and is further provided with a longitudinal threaded bore adapted to receive a set screw 6, which engages the cleaner arm to retain it in position. A nut lock 7 is arranged on the set screw. The shaft may be provided with weakened portions 8 to permit it to be broken off for the purpose of adjustment, and one of the transverse passages is arranged inwardly of each of these weakened portions, as shown in dotted lines in Figure 2 of the drawings. This, however, forms no part of the present invention, it being disclosed and claimed in our prior Patent No. 1 472,644, granted October 30, 1923.

The lower end of the cleaner arm is provided with a suitable retaining device or holder 9 and a cleaner element is arranged in this holder. The cleaner element consists of a backing strip 10 of metal or other suitable material and a rubber strip 11 adapted to engage the surface of the windshield to be cleaned.

As stated, the motor casing is formed in two sections, one of which is shown in detail in Figure 3 of the drawings. Each section of the motor casing is stamped from sheet metal and consists of a tubular portion 12 having a closed end 13 adapted to form one of the cylinder heads. The other end of the cylinder section is flared, as indicated at 14 and is further provided with a recess or cut-out portion 15 for the reception of the closure plate on which the valve mechanism is

mounted. Opposite the cut-out portion 15, the end of the cylinder section is provided with a semi-circular portion 16 and the two semi-circular portions are adapted to aline 5 with each other, forming a bearing for the reception of the power shaft. As shown in Figure 2 of the drawings, the power shaft projects through the cylinder and the handle 17 is adapted to be arranged thereon, the 10 handle being secured to the shaft by means of a set screw 18.

A closure plate 19 is arranged intermediate the ends of the cylinder, the plate being curved in cross section to conform to 15 the cylinder wall, as shown in Figure 1 of the drawings. This plate extends over a portion of the exterior of each section of the cylinder wall and is provided with an inwardly extending projection 20 adapted 20 to be received in the recesses 15. The upper portion of the plate is provided with a lug or projection 21 adapted to be received in an opening 22 formed in a substantially semi-circular clamping member 23. The 25 detail construction of the clamping member is shown in Figure 9 of the drawings. As shown, it is adapted to extend around the cylinder at the point where the two sections are connected to each other and from the 30 top of the closure plate to the bottom. This clamping member is provided with a substantially V-shaped groove 24 adapted to receive the flared ends 14 of the cylinder sections and thus clamp them to each other. 35 The groove 24 is interrupted by an opening 24' which passes over the two component parts 16 of the sleeve bearing for the shaft 4. The two cup-shaped cylinders or casing sections 12 are thereby given additional secure- 40 ment by this embracing relation of the clamping band 23 to the sleeve bearing parts 16, the latter projecting through the opening 24'. In actual practice, the joints between the 45 cylinders 12, the closure plate or central motor attaching member 19, and the clamping band 23, leak to such an extent as to permit ample passage of atmospheric air into the space between the pistons herein- 50 after described. This also is an advantage in facilitating and expediting the manufac- 55 ture of the motor because it is not a pre- requisite to have an air tight joint between said cylinders and clamping band, the band serving primarily to secure the cylinders and the closure plate rigidly together. The in- 60 clined walls of groove 24 cam on the securing parts 14 and act to draw them together as well as draw the cylinder members and tubes 40 into the central supporting mem- 65 ber 19. The lower end of the clamping element is provided with ears 25 having openings 26 for the reception of screws or other fastening elements which are received in threaded openings in the closure plate. 65 Within the cylinder, we provide a pair

of spaced pistons, each of which comprises a plurality of disks 27 of metal or other suitable material having a packing strip 28 arranged between them. This packing strip is of larger diameter than the diameter of 70 the cylinder, forming a flange 29. The parts of the piston are secured to each other by a bolt 30, passing through openings in the metal plates. The two pistons are connected to each other by means of a connect- 75 ing member 31 having offset ends 32. These offset ends are provided with openings for the reception of the bolts 30. Intermediate the offset ends, the connecting member is provided with spaced openings 33 forming a 80 rack. A segmental gear 34 is mounted on the power shaft and this gear is provided with teeth 35 adapted to mesh with the rack. The upper portion of the gear is provided with an arcuate surface 36 curved on a 85 radius from the center of the shaft, and at each end of the arcuate portion, there is provided a shoulder 37.

The closure plate is provided with a pair of longitudinally extending passages 38, 90 communicating with transverse passages 39 extending through the thickened portion 20 to the interior of the cylinder. The outer ends of the passages 38 are connected to conduits 40 which extend longitudinally of the cylinder and communicate with the opposite ends thereof through openings 41 (see Figure 4). The closure plate is further provided with a passage 42, having a tube 43 arranged in its outer end. This tube is adapted to receive a suitable conduit (not shown) which is adapted to be connected to the intake manifold of an internal combustion engine (not shown) or other suction producing means. Intermediate the ends of the closure plate, the passage 42 communicates with an angularly disposed passage 44. As shown, the passage 44 is reduced in size adjacent its upper end and is provided with a valve seat 45'. The lower portion of the 1 passage is threaded and is adapted to receive a threaded valve stem 46, having a valve 47 formed on its upper end. The valve stem projects from the closure plate and is provided with a knob or handle 48. The upper end of the inclined passage 44 communicates with a transverse passage 45 arranged between the passages 39 (see Figure 6).

The suction passage 45 is adapted to be connected to either of the passages 39 and suitable automatic valve mechanism is provided to alternately connect the passages 39 to the suction passage 45 to reciprocate the pistons in the cylinder. As shown, a pin 1 49 is arranged on the inner face of the closure plate for supporting a valve shifting member. The valve shifting member comprises a main portion 50, pivotally mounted on the pin 49 adjacent its lower end and 1

curving upwardly. The upper end of this member is provided with an angular extension 51 adapted to be arranged over the arcuate portion 36 of the segmental gear. 5 Adjacent the bottom, the valve shifting member is provided with a loop 52 and an arm 53 extends upwardly from this loop. The arm is pivotally mounted on the pin 49 whereby the valve shifting member is supported at two points. The upper portion of 10 the arm 53 is provided with an arcuate face 54, curved on a radius from the center of the pin 49 and shoulders 55 are arranged at the opposite ends of this arcuate face. A coil 15 spring 56 is connected at one end of the loop 52 and the other end of the spring is connected to a pin 57 mounted on the inner face of the thickened portion 20 of the closure member. A valve supporting member 58 20 is arranged adjacent the valve shifting member. As shown, the valve supporting member is provided with an opening 59 adapted to receive a pin 60 carried by the closure member adjacent the top of the cylinder to pivotally support this member. 25 The valve supporting member is further provided with a central cut-out portion 61, adapted to loosely surround a sleeve 62 extending inwardly from the closure member 30 and receiving the shaft 4. The valve supporting member is provided with a projecting finger 63 which is arranged above the arcuate face 54 of the valve shifting member and is adapted to engage the shoulders 55. 35 A valve 64 is mounted on the opposite side of the valve supporting member, the valve being cup or dish shaped and being adapted to extend over the suction passage 45 and one of the connecting passages 39 to establish communication between the source of 40 suction and one end of the cylinder, as shown in Figure 6 of the drawings. This valve is provided with a stem 65 passing through an opening 66 in the valve supporting member. The lower end of the valve supporting member is provided with spaced projections 67 which are arranged on opposite sides of the pin 49 to limit the movement of the valve supporting member 45 to properly position the valve each time it is moved.

In operation, the manually controlled valve 47 is opened when operation of the cleaner is desired, by turning the knob 48 and the cleaner motor is then placed in communication with the source of suction or pressure. In Figure 4 of the drawings, the valve shifting member is shown moved to the right and the valve is then in a position to 50 connect the right end of the cylinder to the source of suction. The pistons then move toward this end of the cylinder, oscillating the gear and shaft in a counterclockwise direction. As the gear moves, the shoulder 57 at the right of the cylinder moves toward 55 the angular extension 51 of the valve shifting member. As the pistons approach their limit of movement, the shoulder engages the angular extension to move the valve shifting member in a counterclockwise direction. 70 The initial movement of the valve shifting member is by contact with the shoulder 37 and is at the same speed as the speed of the gear. During this movement, the left shoulder 55 of the arm 53 moves away from 75 the finger 63 of the valve supporting member and the right shoulder approaches it. The spring 56, connected to the loop 52 is initially under tension tending to draw the lower end of the valve shifting member in 80 a counterclockwise direction and the valve shifting member is shown at its limit of movement in this direction in Figure 4 of the drawings. A line connecting the ends of the spring is then below the pin 49. As 85 the valve shifting member moves in a counterclockwise direction, the line connecting the ends of the spring moves upwardly above the pin 49 and the valve shifting member is then snapped or shifted to its 90 other position. Substantially at the instant when the valve shifting member is snapped to its second position, the right shoulder 55 of the arm 53 engages the finger 63 to shift the valve supporting member 95 and the valve. The valve is thus positively shifted with a snap or quick action and the possibility of the valve stopping on dead center is eliminated. The movement of the valve supporting member is limited by an 100 engagement of the shoulders 67 and the pin 49. The opposite end of the cylinder is then connected to the source of suction and the pistons move in the opposite direction to turn the shaft and the segmental gear in 105 a clockwise direction. The operation of shifting the valves when moving in this direction, is substantially the same as that heretofore described and repetition is deemed unnecessary. 110

While we have shown and described the valve actuating mechanism, the present application is limited to the cylinder construction and the valve actuating mechanism forms the subject matter of a divisional application filed January 24, 1925, Serial No. 4,607. 115

It is to be understood that the form of our invention herewith shown and described is to be taken as a preferred example of the same, and that various changes in the shape, size, and arrangement of parts may be resorted to without departing from the spirit of the invention or the scope of the subjoined claims. 120

We claim:

1. In a fluid pressure motor for windshield cleaners, a central member having three fluid passages opening through one face thereof, one of the fluid passages being 125

adapted for connection to a source of suction and the other fluid passages opening through the opposite ends of said central member, a pair of cylinder members having 5 their outer ends closed and their inner ends abutting each other, tubes connected at their outer ends to the outer ends of said cylinder members and having their inner ends detachably connected to the respective end 10 opening fluid passages of said central member, a valve cooperating with said face of said central member to connect the suction passage alternately with the other passages whereby the outer ends of said cylinder 15 members are alternately brought into communication with the suction passage, connected piston elements arranged in the cylinder members, the unconnected passage opening communication between the outer 20 end of its cylinder member and the space between said piston elements, valve actuating mechanism for shifting said valve operable from a moving part of the motor, and clamp means rigidly connecting the cylinder 25 members to said central member in an air-leak joint whereby atmospheric pressure may enter through the space between said piston elements into the communicating outer end of said cylinder members for alternately acting upon said piston elements, said clamp means acting to secure the inner ends 30 of said tubes to said central member.

2. In a fluid pressure motor for windshield cleaners, a pair of cup-shaped cylinder members, a tube for each member secured to the closed end thereof and arranged exteriorly thereof extending toward its open end in spaced relation, a central member for mounting the motor, said central member 35 having end passages to receive the unsupported ends of the tubes and support the same, said cylinder members having their open ends arranged in opposition to each other and supported on said central member 40 for forming a casing, a piston arranged within the casing, valve mechanism for operatively admitting fluid pressure through the passages of said central member to operate the motor, and clamping means interlocked with 45 the open ends of said cylinder members for securing the latter to each other and to said central member.

3. In a fluid pressure motor for windshield cleaners, a pair of stamped sheet metal, cup-shaped cylinder members arranged with their open ends abutting to form a casing, the marginal portions of the abutting ends being cut out to form an opening, a closure plate for the casing opening thus 50 formed, said plate consisting of a casting having an inward enlargement projecting through said casing opening and embraced by the surrounding edges thereof, a shaft journalled in said plate and extending through 55 the inward enlargement thereof into the cas-

ing, a piston operable in the casing for actuating said shaft, and a clamp embracing the cylinder members about their abutting ends and acting to draw them closer together, said clamp being detachably secured 70 to said closure plate.

4. In a fluid pressure motor for windshield cleaners, a pair of cup-shaped cylinder members having their open ends arranged toward each other to form a casing, 75 the marginal portions about the open ends being flared in part and cut out in part, a central supporting member having a part receivable in and embraced by the cut-out marginal portions, a piston operable in the 80 casing, an element mounted on said supporting member and operable by said piston, a clamping band passed about said cylinder members and having a groove to receive the flared marginal portions to secure said 85 cylinder members together and in tight embrace with said supporting member, and means for securing the ends of said clamping band to said supporting member.

5. In a fluid pressure motor for windshield 90 cleaners, a casing formed of a pair of axially aligned cylinder members having flared abutting ends, said flared ends having complementary cut-outs and laterally directed sleeve bearing parts a central member supporting 95 said cylinder members and having a part extending through the cut-outs into the casing, a piston operable in the casing, a wiper actuating shaft journalled in said part of the central member and extending through 100 said casing and said sleeve bearing parts, means for operating the shaft from said piston, a clamping member embracing the flared abutting ends of said cylinder members and having an opening receiving said 105 sleeve bearing parts, means for connecting the clamping member to said central member, and means for operatively admitting fluid pressure to the casing.

6. In a fluid pressure motor for windshield 110 cleaners, a casing formed of aligned cylinder members having abutting ends, each abutting end having a semi-cylindrical part extending laterally and forming with the corresponding part of the companion cylinder 115 member a bearing sleeve, a central member supporting the cylinder members, a piston operable in the casing, a shaft journalled in said central member and in said bearing sleeve and operable from said piston, means 120 for operatively admitting fluid pressure to the casing, and a clamping member passing about the abutting ends of said cylinder members and securing the same to said central member, said clamping member embracing said bearing sleeve to hold its parts together.

7. In a fluid pressure motor for windshield 125 cleaners, a casing comprising a pair of aligned cylinder members abutting end to end, the 130

abutting end portions having securing parts, a central member supporting said cylinder members and having fluid passages, a tube for each cylinder member having one end secured to the outer end of its cylinder member and extending alongside thereof toward the abutting ends of said cylinder members, the inner ends of said tubes being in communication with a respective fluid passage in and supported by said central member, said connections between the tubes and the central member being maintained by securing said cylinder members against separation, a piston operable in said casing, a shaft 15 journalled in said central member and operable by the piston, means for securing the cylinder members against separation and to said central member, said securing means having camming parts engaging the securing parts of said cylinder members and acting to draw the latter toward each other and to maintain the connections between said tubes and said central member, and means for operatively admitting fluid pressure to 25 the casing for actuating said piston.

8. In a fluid pressure motor for windshield cleaners, a casing formed of a pair of cylinder members having abutting end portions provided with securing parts by which the cylinder members may be drawn toward each other, a central member supporting the cylinder members, a piston operable in the casing, a shaft supported by said central member and operable by said piston, a 30 clamping band anchored at one end to said central member and passing about the abutting ends of said cylinder members, said

band having parts engaging said securing parts of the cylinder members in camming relation to draw said cylinder members 40 toward each other, and means for securing the opposite end of said band to said central member and tightening the band about said cylinder members.

9. In a fluid pressure motor for windshield 45 cleaners, a casing formed of a pair of cylinder members having abutting ends provided with complementary cut-outs, said cut-outs forming a central opening in the casing, a central member supporting the cylinder 50 members and having a part projecting into the casing through the casing opening, said part having a suction passage and a pair of fluid passages opening through the inner face thereof into the casing, connections 55 between the fluid passages and the opposite ends of the casing, one fluid passage for each end of said casing, a piston operable in the casing, a wiper actuating shaft journalled in said central member and extending 60 through said part into the casing, means operable by said piston for actuating said shaft, means securing said cylinder members to said central member, and valve mechanism operable over the inner face of said 65 part by and during movement of said piston for alternately connecting said fluid passages to said suction passage and open the unconnected fluid passage to atmospheric pressure.

In testimony whereof, we affix our signatures.

FREDERICK G. FOLBERTH.
WILLIAM M. FOLBERTH.
